UNITED STATES PATENT OFFICE.

ADRIAN FRANCIS SYKES, OF NEW BARNET, ENGLAND.

ELECTROMAGNETIC APPARATUS FOR RECORDING SOUND.

Application filed August 16, 1926, Serial No. 128,612, and in Great Britain June 22, 1925.

This invention constitutes an improvement in or modification of my invention as claimed in British specification No. 210956. According to that specification sound is recorded in electrical fashion by means of an electromagnetic engraving device of oscillographic type comprising a working conductor or conductors consisting of one or more strips of metal generally in tension and located in a magnetic field. The vibration of the strip or strips in response to forces derived from electric currents of a telephonic nature is utilized to produce a sound record. Elastic control of the strip or strips is the chief feature of the invention and the minimum of mass is a desideratum. In some forms of such apparatus considerable forces are brought to bear on the framework or floating weights and it is the object of the present invention to relieve the framework or floating weights from such forces as are liable to set up undesirable resonance effects. The invention more particularly applies to the case in which the air gap of the field magnet is on one side of the wax tablet or record blank. With such apparatus it is possible if desired to obtain aperiodic response over a wide range of frequency. The first part of my invention relates then to means for annulling the electro-mechanical effect on the structure or on a floating beam. The second part is concerned with means for obtaining a wide range of action as regards amplitude of vibration in a simple form. The third part of my invention is connected with the concentration of the resistance of the working conductor and also of the magnetic field. The fourth part of my invention involves considerations pertaining to damping the vibration of the working conductor.

According to the first and main part of my invention I provide a further conductor adjacent to the working conductor immersed in substantially the same field, or in a similar field, and adapted to produce electro-magnetic forces substantially equal and opposite to those produced by the working conductor. This subsidiary or compensating conductor may be fixed to the structure or it may be able to vibrate either in free relation to the structure or damped with respect thereto. Preferably the working conductor and the

compensating conductor are carried on a floating weight so that the electromagnet which is of considerable mass is fixed. A convenient method of applying the invention consists in forming the compensating conductor and the acting conductor from one strip or wire by bending it back on itself in U or V form; a special case is where this combination is realized in the shape of a solenoidal winding of many turns forming a high resistance recording element. The invention further consists in the improved recorder and the subordinate details and method of working hereinafter described in connection with Figures 1 to 13 of the accompanying drawings.

According to the second part of my invention the strip traversed by the current is corrugated transversely to the length either wholly or partly. The strip so corrugated is or may be put into any desired state of tension at the time of fixing.

According to the third part of my invention I shape the conductor or conductors operating the magnetic air gap of a recording appliance of the type set forth in my British specification No. 210956 in order to increase the force available where required relatively to the power expended in the conductor due to its ohmic resistance. Thus the portions adjacent to the anchorings which do not move much may with advantage be thickened or widened or both together. The result of such procedure is to obtain what amounts to an isthmus with properties varying with the proportions adopted and determinable by mathematics or by experiment. In this way the effective resistance is concentrated on the reduced or restricted section where the motion incidental to vibration is greatest. It will generally be advantageous to shape the polar extensions to correspond so as to obtain the greatest possible concentration of magnetic field where most required.

According to the fourth part of my invention the natural vibrations of the recording element are damped by means of the valve supplying current thereto. This can only be made really effective by the use of very intense magnetic fields and very low effective resistances of conduction strip. It is more easy to obtain useful damping in this way

when the natural frequency of the parts is not excessively high. I may supplement the electro-magnetic damping by mechanical damping as hereinafter set forth.

5 In the accompanying drawings:—

Figures 1 to 4 are diagrammatic views showing the general principles of the invention.

Figures 5 to 21 show different arrangements of the conductor which operates the stylus and its immediate connections.

Figures 22 and 26 show forms of the complete apparatus.

Figures 1, 2, 3 and 4, illustrate in diagram my invention and more particularly the first and main feature which consists in immersing the portion of the conductor which operates the stylus and its return portion in a magnetic field of uniform density or in parts of the same or different fields of the same density.

The stylus 3 which engravés the record 4 is mounted with its connections upon a block 65 of ebonite or other suitable material 25 which is pivoted at 66 about some suitable fixed support 125, the structure thus constituting a floating beam or "balance weight". The weight of the beam is partly borne by a smooth ball or shoe 89 which rests upon 30 the wax record and is carried adjustably by a screw 90 to regulate the depth of cut. Alternatively this depth may be determined by the well known gravity method. According to my invention the conductor 1 is bent

35 back upon itself so as to form with its return part 306 a U shaped strip the ends of which are attached by soldering or other means to conducting plates or strips 107, 109, of copper, aluminium or other suitable

40 metal. These plates lead to the ring 85 which forms the secondary circuit of the transformer which delivers the electric current for operating the conductor 1. For clearness the arrangement of the conductor

45 is shown separately in Figures 2 and 3, the separation between the conductors being somewhat exaggerated. The primary of the transformer is not shown. The conductors 107, 109, are separated by insulating mate-

50 rial 111 which may be mica or ebonite, and the whole assemblage is bolted as at 307 to the body 65. Tension may be put on the U shaped strip 1, 306, by a lever 83 having a springy part 308. This lever is pivoted

55 at 84 and adjusted by a screw 82. A suitable method of connecting the U shaped strip to the lever is to thread it through a slot 309 in the end of the lever as shown in Figure 4. The whole or substantially the whole of the

60 strip 1, 306, is situated between the poles 9, 10, of a magnet (Figure 3). One of these poles is also shown by dotted lines in Figure 1. Both poles are on the same side of the record. In the case shown, the magnetic

65 field, or the part which matters, is of uni-

form density, but if this is not the case the conductors 1 and 306 should be immersed in parts of equal density.

In Figure 5 the strip which is deformed by the vibration forces is constituted by a winding of a few or many turns lying side by side like a flat solenoid, and the object of such a construction is the transference of the transformer to a more remote part so that it need no longer form an integral part of the recorder. A slight variation in the method of mounting is indicated; thus the lever 83 adjusting the tension passes through a slot in the balance weight and the end of this lever is forked or slotted to provide for the insertion of a pin 311. The other end is anchored also to a slotted lever 310 with a pin 312 and the coil is strained between the two pins. Either the movable lever or the fixed anchorage or both may have a certain degree of flexibility to accommodate the very slight motion of the ends of the vibrating portion due to flexure rather than complete immobility. Both these elastic portions may be damped with thick grease. As shown the recorder is engaging with a disk blank 28 for the purpose of engraving a hill and dale record. The sliding ball and its adjustment and also the field magnets are omitted for simplicity. Twisted leads 313 convey current from the input terminals 313 to the winding 1, 306. It is preferable to stick these leads down to the various surfaces.

A form of the invention suitable for recording a lateral cut record is indicated diagrammatically in Figure 6. The strips 1 and 306 are arranged in bifilar fashion and strained between the anchorings 309, which are metallic studs insulated the one from the other, and the stud 81 which is the movable stud and is controlled in similar fashion to that shown in the foregoing figures by a lever and micrometer screw. The field magnet pole pieces are indicated by dotted lines at 9 and 10, and the two branches of the conductor 1 oscillate in opposite phase, as in bifilar suspension perpendicularly to the plane of the paper. The compensating portion of the conductor 306 is preferably fixed to the body 65 throughout its length so that only the working portion 1 is free to vibrate or is stretched and the portion 306 is preferably of increased section compared with the portion 1. The terminals of the portion 306 are shown at 306^a. In this figure the sliding ball 89 is shown controlled by a springy lever 118 and micrometer screw 90. This ball either runs immediately beneath the magnetic air gap which then has to be made wide enough to permit of this or the lever and ball are located in the space between the polar surface and the wax blank. Another method is to drill or cut away one of the pole pieces to provide the necessary

room. Instead of making the bifilar movement from a single conductor it may be built up from a bundle of insulated conductors forming a high resistance winding. 5 Figure 7 is concerned with the field magnet and its relation to the balance weight and the blank to be recorded. The polar extensions 9 and 10 are braced together by brass plates one of which is shown at 314. 10 The yoke of the magnet is bushed by rubber 315 to provide a cushion support on the bearers 316 which may be cemented into a brick wall or pillar. A very high intensity of magnetism in the air gap is aimed at and 15 the concentrated field is more especially brought to bear on the region where the greater detection occurs. By using the strongest possible field the value of the electromagnetic damping is increased. The 20 illustration shows the poles 9 and 10, the disk blank 28 being rotated beneath the recorder. The pivots of the balance weight 65 are in the line 66. The sliding ball is shown at 89 and the micrometer adjustment 25 at 90.

Figures 6 to 13 are diagrams indicating possible modifications and methods of working. Thus in Figure 8 the recording element 1 is partly corrugated and partly in 30 the form of a lever pivoting about the point 1^a where it joins on to the compensating portion 306 which is fixed to the block 65. Crosses indicate the direction of the magnetic field, the poles being out of the plane 35 of the paper. In Figure 9 the compensating portion is in the form of a tube and the electrical and mechanical connection of the elements 1 and 306 is by means of a small metallic diaphragm 317, about which 40 the element 1 oscillates as in the case of Figure 8. Any form of damping material 318, such, for instance, as oil, petroleum jelly, wool, felt, sawdust, rubber in the form of a bush, pellets or sponge, may be placed 45 in the space between the tube and the vibrating element 1, as indicated by the horizontal shading. A form of instrument in which the poles are removed further from the surface of the wax tablet is shown in Figure 10. 50 Here a bifilar operating conductor 1 is connected to a stylus rocker 319 by cords or links 320 passing down the holes 321. The stylus rocker rests on and is pressed against two pivot points, one of which is shown at 55 322. 324 is a damping chamber and a glass cover plate 323 renders it totally enclosed and the oil contained in it also fills the holes 321 and is retained by capillarity. The 60 compensating conductor is bedded down on the ebonite and is of greater section than the working strips 1.

Figures 11 and 12 are diagrams setting out in side elevation a form of bifilar movement suitable for lateral recording. The 65 rocker 319 is connected by a torsion wire 325

to the straining lever 83 and the wires are stretched over the fixed peg 81 to the fixed ring 85. Figure 12 is an explanatory plan view showing the conductors illustrated in the preceding figure stretched out in line, 70 that is, unfolded from the pin 81 and flattened out.

Figures 13 and 14 show an arrangement of the conductors 1 and 306 adapted to an apparatus in which the entire field magnet 75 system is laminated and itself constitutes the input transformer. Figure 15 shows the general arrangement. The conductors 1 and 306 are connected by conducting members indicated by the numeral 85 in Figure 12, 80 all four forming a closed circuit which is situated between the poles 9 and 10 of a field magnet having a laminated core. The leads for the input which operates the conductor 1 are connected to a winding 11 which may be 85 the field magnet winding. This magnet in conjunction with the circuit 1, 85, 306, thus also constitutes a transformer, the winding 11 being the primary and the circuit the secondary. The field magnet battery leads are 90 provided with suitable chokes 12. The field strength acting on the conductor 306 is substantially the same as that acting on the portion 1. Means for stretching the conductor 1 are provided by the screw 82, and 95 the interspace bounded by ring circuit 306, 85, 1 may be filled in with ebonite 326 and partly with damping material 318 which latter may take the form of a brush. 65 indicates the floating beam and 66 its pivot as 100 before.

Figure 16 shows a solenoidal winding 1, 306, stuck on to the projection 327 from the floating beam 65 and intended to be immersed in a magnetic air gap. In this case 105 the portion 306 is non-vibratile. A second winding may be incorporated with this solenoidal winding and more or less short circuited to provide electromagnetic damping.

In operating the recorder as hereinbefore 110 and hereinafter described, valve correction circuits for co-ordinating the properties of the primary detector, the recorder, and the reproducing system are very desirable and form part of the equipment. Such circuits 115 are described in British specifications Nos. 160,223, 220,420 and 190,840 among others. An elaborate equipment would also include rejectors for dealing with any troublesome resonances however arising. The natural 120 frequency of the apparatus may be set to approximate to 750 cycles a second or in that region, and full correction made for this tone and its damping. In numbering the various details I have taken account as far 125 as practicable of the number allotted to similar details in my previous specifications.

Figure 17 indicates the vibrating element 1 partly corrugated, also the end 340 of the portion 306 is shown enlarged to provide ad- 130

ditional area of contact for the screw or solder securing the strip. The conductor 306 is attached to or forms part of the return conductor 109 and the element 1 is connected to air extension 107. The parts 107 and 109 are separated by mica or like insulation 111. This figure deals with apparatus for producing hill and dale records.

Figure 18 is a fragmentary section through the members 1 and 306 of a device applying the invention to the production of needle cut disks by means of a bell crank lever 341 pivoted on an axis 342 to a pair of bosses 343 formed on the detail 306 and actuating a cutting stylus 3. Between the corrugated strip 1 and the bell crank lever 341 is a pad of shellac 344 or other coupling means for the purpose of transferring the vibration of the strip to the lever. I may employ bell crank levers of varying ratios of mechanical magnification according to circumstances. In place of the method of pivot points or bearing illustrated, a pair of metallic studs or wires or a leaf may be substituted so as to form an elastic hinge capable of taking up the slight lateral drift consequent on the angular displacement of the bell crank lever when in vibration. Figure 19 shows the operative conductor 1 reduced in section at the central region by a gradually restricted width as shown at 399. If this conductor is of aluminium it may be fixed to the bars denoted by 306 and 107 in Figure 19, the current being supplied by means of small screws as at 83; otherwise it may be soldered. It is to be understood that this conductor may be stretched by any well known means and used as in the foregoing drawings. The polar extensions are curved to the configuration of the operative conductor.

Figure 20 provides for a diminished depth of conductor with or without any alteration of width. In this case it may be desirable according to circumstances to articulate the junctions with the conduction limbs 107 and 306 and if necessary to provide supplementary conductors of a flexible nature to guard against the uncertain resistance of the articulate joints. As an electrical alternative to energizing the operative conductor and compensating by telephone currents or derivatives thereof, one may pass a heavy constant current through these and allow the telephone currents to vary the magnetic field. Should this course be adopted it would be advisable to laminate the field magnet and to design it on a much smaller scale. On this system there would be a considerable amount of self induction and this would have to be taken account of as affecting the characteristic response.

The principle of grading the section of the conductor either independently or in association with the configuration of the magnetic poles is not only applicable to the par-

ticular strips shown in the illustrations but applies generally to the apparatus dealt with in this specification and to all electrodynamic equipment. The grading of simple strips may so alter the resilient properties of the strips that corrugations or other deformations of the material may be desirable to counteract the effects.

Although a graded strip or structure is particularly suitable for operation with a high natural frequency of the moving parts I do not restrict myself to any particular natural frequency but may use frequencies of 7000, 6000, 5000, 4000, 3000, 2000, 1000, 500, 250, or intermediately. Naturally the properties of a recorder vary with the proportions of the essential constants. Moreover, in a recording system the constants of every link in the process are involved including the tones of the recording studio. This being so an elaborate equipment would include means for correcting for the tone or period of vibration of the recorder, means for generally tilting the frequency scale, means for superposing integrations or differentiations of the original potentials derived from the primary detector, blunt rejector or acceptor circuits, rejector and acceptor circuits in general for dealing with casual resonances, corrections for the type of sound box to be used in reproduction, high pass and low pass filters for terminating the scale abruptly. When a brilliant record of the nature of the pressure wave in the air is aimed at, either a suitable microphone is chosen or the effect obtained by differentiation. Such a record is suitable for a large diaphragm sound box or other integrating device. The properties of transformers are available for modifying the scale characteristic especially as a means for omitting the lowest frequencies which limit the volume without contributing much to the total effect.

Figure 21 illustrates the application of damping to the operative strip by petroleum jelly 318 applied in the vicinity of the anchorage and the method of absorbing the energy of the natural vibration by means of a cord 400, which may be stranded metal cable, threaded through an attachment 401 to the strip and knotted as shown at 401 and leading either to a loose coil or simply secured to a distant support. Vibration travels from the element and attachments along the cord in the form of a ripple which is generally absorbed without reflection. By using a comparatively dense twisted cable and a fluffy covering the absorption of energy is facilitated. This method of damping in general has been wholly or in part described and claimed in my British specification No. 31818 of 1925. In place of attaching the ripple absorbing cord, strip or sheet, to the acoustic element as shown, the anchoring 93 of the conductor 1 to the conduc-

tor 306 may be articulated or made in the form of a hinge and the strip continued indefinitely on the side remote from the stylus so that ripples generated in the conductor 1 5 are lost in applied damping material, such as a wool covering wound on or applied to the indefinitely continued strip.

Figures 22 and 23 show an electromagnetic movement constructed according to the 10 invention, Figure 23 being a plan view from underneath of Figure 22. The corrugated strip 1 is stretched or placed between the conducting extension 107 and the compensating conductor 306, itself forming part of the 15 return conductor 109, the parts 107 and 109 being insulated the one from the other by mica 111 and soldered to the ends of the secondary winding 85 of the transformer with core 88 and primary winding 141. 20 The secondary winding 85 is formed of one or more turns of copper strip on edge forming a spiral or volute. In this particular design if desired this secondary winding may be approximately square and used in 25 conjunction with a core to correspond. An ebonite block 65 with bolt 333 and screws serves to clamp the whole together, while a block 334 bushed with rubber 335 and a metallic spindle 336 forms the axis of pivoting 30 66. The sensitive element 1 is strained between two screws 81 and a tag 337 may be left for the purpose of inserting a hook into a hole 337^a whereby tension may be put on the element previous to clamping down or 35 soldering in position. The fixing done, this tag may be clipped off. Damping composition 318, which may consist of petroleum jelly, is inserted between the element 1 and the compensating conductor 306. By making the strip sufficiently short, for instance, about five eighths of an inch long, a natural period of some thousands of vibrations a second can be obtained without any difficulty.

In the plan view a dotted trace of the field 40 magnet poles 9 and 10 and a bracket 114 supporting the transformer core are shown. It will be seen that the conducting section 107 makes contact with the inner convolution of the secondary winding 85 conventionally denoted by portions of concentric circles. When complete the space between the convolutions is filled in with melted shellac and the whole assemblage forms a composite floating beam. A magnetic shield 338 is also 45 indicated by dotted lines and is supported on the field magnet by brass distance pieces or studs 339. This shield is a useful feature when the apparatus is used in conjunction with commercial phonographs and it is 50 found necessary to prevent the magnetic leakage from interfering with the motion of the feed carriage or the equivalent. Generally speaking it is convenient and advantageous to operate a recorder of this class 55 by means of two stage transformations, that

is to say, that the currents from the amplifier are stepped down by means of one transformer and again transformed at the instrument itself. The usual sliding ball or shoe which regulates the depth of cut and 70 carries most of the weight of the floating beam on the wax blank has been omitted in these illustrations.

Figure 24 shows the field magnet having 75 polar extensions 9 and 10 attached to the electromagnet cores 7 which latter are strengthened by the bracing 314.

Figure 25 shows the general lay out of an apparatus constructed according to my invention. Particular forms, such as those 80 shown in Figures 22 and 23 or in Figure 26, may be supposed to be embodied in it.

The field magnet, one of whose poles is shown at 10, is clamped between a bracing member 314 hinged on a pin 384 and a housing 114 designed to support the transformer core 88. The pin is held in the vertical member 385 mounted on a shaft supported in bearings 387. A lever 388 grips the shaft and serves to twist the whole apparatus in 90 the bearing for adjustment by means of the screw gear 389. On top of the member 385 is a further screw adjustment 390 engaging with the magnet structure by means of a flexible joint 391 such as a ball and socket 95 joint, which arrangement permits the magnet structure to be raised or lowered relatively to the revolving blank 4. The blank is driven by a phonograph 392 which is itself supported on a cast iron base plate 393. 100 Magnetic effects are shielded from the metal of the phonograph by a magnetic shield 338 projecting out from the brass studs 339. A switch 394 is provided for the field coils. The transformer winding 141 is wound on 105 an ebonite bobbin 395 and cap 396 and leads directly to the valve circuit. To prevent saturation of the magnetic core by the steady anode current an air gap is provided in the central part of the core at the region shown 110 dotted and denoted by 397. Other methods for dealing with the problem include short circuiting the secondary winding by a large inductance but of low resistance; in such 115 circumstances one may insert a condenser and so prevent any direct current in the secondary winding. A brass lever 398 serves as a means for lowering the balance weight on to the surface of the blank.

Figure 26 is a diagram showing the recorder and associated details, the general 120 position of which is set out in Figure 25. The details comprise a transformer with laminated core 88, a primary winding section-wound 141 located on an ebonite bobbin 402, a secondary winding 85 of a few turns of copper strip on edge insulated and bonded by melted shellac forming part of a composite floating beam pivoted about an 125 axis 66. Other parts of the floating beam 130

are a block of brass 334 attached to the secondary winding and bushed with rubber 335 through which the spindle 336 passes, a counterpoise 73, an ebonite bracing block 55 bonding the parts 107 and 109 which are extensions of the secondary winding insulated the one from the other by mica 111, the working conductor 1, and the compensating conductor 306, which latter is integral with the extension 109. The working conductor is here shown corrugated, stiffened in the centre by dishing or embossing, and connected with a stylus bar 3. Supplementary damping material is here shown 10 as at 318 and may be vaseline or felt or both. This material is for the purpose of 15 checking overtones which are not effectively dealt with by the electrical damping provided by the resistance of the power valve 20 circuit. At 80 is shown the trace of the polar region on either side of the parts 1 and 306, both poles being on the same side of the record blank. The conductor 1 is tensioned or regulated by the locked block 405 25 and screw adjustment 82. A sliding shoe 89 takes the weight of the beam on the smooth surface of the blank. This shoe is carried on a springy arm with grease damping in the slot 412. With this arrangement of operating and return conductors wholly immersed in the magnetic field, forces due to the action of the telephonic currents are 30 completely or substantially annulled since they act in opposing directions and so the 35 floating beam and also the magnet structure are relieved from their influence. This fact is of considerable practical importance since it prevents sudden changes in the mean 40 value of the power valve anode current from producing any resultant force on the beam.

Connected with the recorder is shown the general amplifying valve system which of course varies according to circumstances, it being an inherent advantage in electrical 45 recording that the wave form and magnitude of the potentials derived from the microphone can be controlled either during the recording process or otherwise. As the devices for this purpose are numerous their 50 presence is merely indicated by one example. Thus from the input transformer 406 the incoming potentials from the microphone act on valve 44 in the plate circuit of which are an inductance 408, a resistance 407 and 55 a condenser 409, which combination gives at will control over the frequency scale, that is to say, allows either the high frequency harmonics or the low frequency harmonics to predominate. The inductance, resistance 60 and capacity are of course variable to any extent necessary. The resulting potential controls valve 46 and thus the power valve 47 via the intervalve transformer 410. Other details are:—microphone pads 406*, polarizing batteries as at 158, grid leak 162, grid 65

condenser 196, low tension bus bars 169 and 170, earth plate 173, high tension bus bars 171 and 171'. Obviously intermediate valves may be added also with correction devices corresponding to 407, 408, and 409, 70 and other circuit arrangements. By arranging that the ratio of transformation of the recorder transformer 141, 85 is sufficiently great, the resistance of the secondary circuit which is chiefly the resistance of the strip 1 may be great compared with the resistance of the power valve, in which case the strip acts as though more or less short-circuited and hence experiences damping forces appropriate to the motion of such a 80 conductor in a strong magnetic field.

Recorders constructed according to the invention can be operated from any form of microphone but for high grade work one of aperiodic type is desirable. Electro-magnetic microphones constructed according to British specifications Nos. 160228, 222420 and 224936 (Sykes and Marconi Company) are suitable. Inasmuch as the control of the recording element is for the most part elastic, or even entirely elastic, the response to current is nominally proportional except near to or above the resonance point. This fact should be borne in mind in comparing this recorder with the type in which the frequency range to be recorded lies almost wholly above the natural frequency of the recording element relative to its support. Practically speaking this means a change of two differentials. Hence a recorder 100 yielding a characteristic response more or less corresponding to the pressure wave will record this wave in terms of displacement on the wax and such a record may be too brilliant or sharp in tone as interpreted by 105 a normal sound box and consequently one or more stages of integration may be required especially in the region of the bass tones. By designing the power valve circuit supplying currents to the recorder suitably a measure of electro-magnetic damping may be obtained; in other words, the valve circuit may damp the vibration of the recording element. Thus if a high ratio transformation is provided the motion of the conductor generates currents in the secondary circuit of the transformer which tend to resist the motion. The resistance of the primary circuit multiplied by the square of the 110 step up ratio gives the resistance of the primary as transferred to the plate circuit. If this is equal to or greater than that of the internal impedance of the valve the damping imposed by the valve is becoming effective. The recording strip may be stretched up to 115 a value nearly equal to the breaking strength of the material and in such a case the frequency may be as high or higher than any frequency of importance in music or speech but of course with a sacrifice of sensitive- 120

125

130

ness. The natural frequency chosen is a matter for discretion. One merit of the compensating conductor in balance weight constructions is the prevention of undue disturbance from unsymmetrical action of the valve characteristics and especially grid current effects.

What I claim is:—

1. An electro-dynamic sound recording device comprising a stylus, a working conductor in operative connection with the said stylus, a compensating conductor in series with the working conductor, a floating beam carrying the said conductors, and means for producing a magnetic field, both conductors being immersed in the said field and in parts of the field of substantially the same strength.
2. In an electro-dynamic sound recording device, a field magnet having its poles at one and the same side of the record blank, a stylus, a working conductor in operative connection with the said stylus, a compensat-

ing conductor in series with the working conductor, and a floating beam carrying both conductors, said compensating conductor being adapted to annul mechanical forces set up electromagnetically in the magnetic structure or the floating beam.

3. In an electro-dynamic recording device as claimed in claim 2, a field electro-magnet between the poles of which the two said conductors are arranged, the compensating conductor being adapted to protect the magnetic structure and the floating beam from mechanical forces arising from currents in the conductor.

4. Apparatus as claimed in claim 1, in which the working conductor consists of a thin corrugated sheet.

5. In apparatus as claimed in claim 1, means for damping the operative conductor.

In testimony that I claim the foregoing as my invention I have signed my name this 5th day of August, 1926.

ADRIAN FRANCIS SYKES.
